CLAIM

The ornamental design for the cigar caddy, as shown and described..

DESCRIPTION

FIG. 1 is a perspective view of the cigar caddy showing my new design;

FIG. 2 is a front view thereof;

FIG. 3 is a top view thereof;

FIG. 4 is a right elevational side view thereof; and,
FIG. 5 is a bottom view thereof.

The broken lines are shown to illustrative purposes only and form no part of the claimed design.

The front view and the rear view of the cigar caddy are the same.

The right elevational side view and the left side view of the cigar caddy are the same.
